UNITED STATES PATENT OFFICE.

HENRY J. DICKERSON, OF APPLETON, WISCONSIN.

SHUTTER-WORKER.

SPECIFICATION forming part of Letters Patent No. 226,045, dated March 30, 1880.

Application filed July 9, 1879.

To all whom it may concern:

Be it known that I, HENRY J. DICKERSON, of Appleton, in the county of Outagamie and State of Wisconsin, have invented certain new and useful Improvements in Combined Shutter and Blind-Slat Operators; and I hereby declare that the following is a full, clear, and exact description of the same, reference being made to the accompanying drawings, in which—

- 10 Figure 1 is a bottom view of the cap C. Fig. 2 is a plan view of the blind-slat-operating device. Fig. 3 is the shaft and chain and their connection. Fig. 4 is a modified form of the locking device employed. Fig. 5 is a horizontal section through the window-casing, showing interior of cap C. Fig. 6 is a plan view of hinge B. Fig. 7 is an elevation of the casing and blind; and Figs. 8 and 9 show the preferred form of locking mechanism.
- 15 20 Like letters represent the same parts.
- The window-casing is represented by *a*, the blind by *b*, the blind-slat by *c*, and the rod connecting such slats by *d*. These parts may be of any convenient construction. The upper hinge, which connects the casing to the blind, may be of ordinary construction. The lower hinge is composed of two parts, *A* *B*, the part *A* being attached to the casing and the part *B* to the blind. The portion *A* is 25 made in two parts, *C* *D*, placed together and screwed to the window-frame. The upper portion consists of an outwardly-projecting hollow cap, and a projection from the part *B*, having a central opening, partly fills the said cap, leaving sufficient space, however, for the easy 30 play therein of the chain *X*, which is composed of flat links riveted together, as shown in Fig. 3. The projection *D* has a spindle, which passes through the central opening in the cap 35 and forms a bearing-surface for the movable hinge *B* to turn on. The end of the chain is formed with a round link or ring, which is placed over the projecting stud on the movable plate *B*.
- 40 45 It is evident that the movement of the chain will cause an axial movement of the hinge *B* on the spindle and will swing the blind.

- A square mortise is cut entirely through the casing of the window, and in such mortise is 50 placed the square shaft *H*, one end of the shaft being connected to the chain *X* and the

other passing through to the interior of the house, where it is provided with a suitable knob. The shaft may thus be pushed in and out, and the blind is operated by such movement.

55

It is desirable in devices of this class that means be provided for not only locking the blind when open or closed, but for adjusting its position when partly open. The means of adjustment employed by me consist of a cam, *O*, through which the shaft *H* passes, as shown in Fig. 12, which is provided with an elliptical slot, in which works an eccentric, *P*, operated by a thumb-lever.

60

A motion of the eccentric in either direction will move the cam and hence rotate the shaft slightly. The frictional contact of the cam with the square shaft is sufficient to hold it against motion, and the locking device may be applied in any position of the blind.

70

A modified form of this locking device is shown in Fig. 4, differing from that already described only in the form of cam and eccentric. In cases where greater strength is required in the locking device I may employ a double friction-cam, the two pawls of which act simultaneously; but usually the single cam described will be sufficient for all ordinary purposes.

The blind-slat operator is shown in Fig. 2. It consists of a forked lever, *K*, attached at one end in any suitable manner to the slat-rod *d*. It is pivoted to the forked plate *i* on the blind, and when such blind is closed passes through a mortise in the case, and its forked end in closes the square shaft. By turning the shaft with the thumb-lever (before described in connection with the locking device) the lever *K* is moved and the slat-rod operated.

The advantages of the device lie in its simplicity, convenience, the ease with which it is operated both as a shutter-worker and a blind-slat operator, and its efficiency for the purpose for which it is intended.

Having thus described my invention, what I claim, and desire to secure by Letters Patent of the United States, is—

1. In a shutter-worker, the combination, with the square shaft *H*, of the cam and eccentric for locking such shaft, substantially as described and shown.
2. In a shutter-worker and blind-slat opera-

tor, the combination of the forked lever K, the shaft H, and the cam and eccentric, substantially as and for the purposes set forth.

3. In a shutter-worker, a locking device consisting of a cam through which the operating rod or shaft passes, in combination with a pivoted eccentric, whereby said shaft is locked by frictional contact with said cam, as set forth.

10 4. In a shutter-worker, the described hinge-joint, consisting of the two-part plate A, fixed to the window-casing and having the upper projecting cap, C, lower projecting plate and spindle, and the plate B on the blind, having a 15 projecting plate provided with a central open-

ing through which said spindle passes, all substantially as described and shown.

5. The described hinge-joint, in combination with the chain and square shaft, as and for the purposes set forth.

6. The shutter-worker and blind-slat operator described, consisting of the hinge-joint A B, chain X, shaft H, cam O, eccentric P, and forked lever K, all constructed and arranged substantially as described and shown.

HENRY J. DICKERSON.
